UNITED STATES PATENT OFFICE.

JOHN B. WELCH, OF SHREVEPORT, LOUISIANA.

DRYING APPARATUS.

Application filed July 19, 1922. Serial No. 575,965.

To all whom it may concern:

Be it known that I, JOHN B. WELCH, a citizen of the United States, residing in Shreveport, in the parish of Caddo and 5 State of Louisiana, have invented an Improvement in Drying Apparatus, of which the following description, in connection with the accompanying drawings, is a specification, like characters on the drawings representing like parts.

This invention relates to apparatus for drying lumber and other materials.

The object of the invention is to provide drying apparatus of novel and improved 15 construction adapted to dry the material in a superior manner under drying conditions which are practically self-regulating, thus insuring the most desirable drying results.

To this end, one feature of the invention 20 contemplates a construction of drying apparatus having provision for the development of a self-controlled recirculation of air actuated primarily by differences in density of the air. Another feature of the invention 25 contemplates the withdrawal of a portion of the hot humid air from the wet end of the dryer and the distribution of this hot humid air to the dry end of the dryer for controlling the air conditions at both the wet 30 and dry ends of the dryer. This is preferably accomplished by the provision of a throat injector in a distributing duct for the positive induction of wet air from the green end and delivery of it to the dry end of the 35 dryer. The withdrawal of the wet air may and preferably will be accomplished by the cold inrushing fresh air or by means of differences in vapor pressures, and in both cases the distribution of the hot moist air 40 from the wet end to the dry end will be self-regulating to maintain the desired air conditions within the dryer.

Other features of the invention will be hereinafter described and particularly 45 pointed out in the claims.

In the drawings the invention is illustrated as embodied in a progressive kiln for lumber drying, wherein Fig. 1 is a vertical section with a portion broken away, showing 50 the elongated kiln; Figs. 2 and 3 are details in side and end elevation, respectively, of a portion of the distributing duct by which hot moist air from the wet end of the kiln is distributed to the dry end of the kiln; Fig. 55 4 is a sectional plan of a portion of the kiln shown in Fig. 1; Fig. 5 is a cross-section on

line 5—5 of Fig. 4; and Fig. 6 is a detail to be referred to.

In drying lumber and other material, the more modern practice contemplates the 60 initial heating of the green material throughout in an atmosphere of sufficiently high humidity to accomplish the heating without evaporation of appreciable moisture from the green material. After the material has thus been heated thoroughly to a sufficiently high temperature, the material is brought into contact with air of gradually decreasing humidity, thereby permitting gradual evaporation of the moisture and preventing surface drying, cracking and other disadvantages. In drying lumber on a large scale progressive kilns are usually employed which comprise elongated chambers often of a length approximating 100 to 75 120 feet. During the operation of the kiln, the lumber is progressively moved from the entrance or wet end of the kiln to the dry or delivery end of the kiln. Provision is made for maintaining the temperature and 80 humidity conditions within the kiln such that the entering of green lumber is initially brought into contact with air of relatively high humidity and at a temperature such that the moisture within and throughout the 85 body of the lumber is raised sufficiently in temperature to provide for the proper amount of evaporation and without evaporation of appreciable quantities thereof. The lumber is thereafter progressively moved to 90 the dry or delivery end of the kiln, and in the course of its movement it encounters air of progressively decreasing humidity, so that the moisture is caused to gradually 95 evaporate in a manner such as to avoid surface drying, cracking and similar difficulties.

The success of the operation of such kilns has heretofore depended to a large extent upon the care with which the humidity and temperature conditions within the different 100 portions of the kilns have been controlled by the operator, and particularly at the dry end thereof. Automatic humidity controllers for injecting moist air by means of steam sprays into the kiln have been employed. These attempts, however, to assist in controlling the humidity conditions within the kiln have generally resulted in the stoppage of circulation within the kiln, the excessive use of live steam thus adding 105 considerably to the cost of operation; and furthermore, because the addition of mois- 110

ture in the form of steam reduces to some extent the rate of drying. Attempts have also been made to induce positive circulation by means of blowers and fans, but the installation of such equipment is expensive, the initial investment is high, and the upkeep cost on the blowers and general apparatus is considerable. From the drying standpoint, a blower kiln is exceedingly dangerous unless very carefully watched by the operator. Many of these kilns have been used throughout the country and a great many discarded because of the fact that whenever the temperature or humidity gets beyond the control of the operator through his carelessness or otherwise, the lumber or material is ruined very quickly because of the high velocity of air movement throughout the lumber.

In certain other types of progressive kilns, the fresh air is admitted directly under the dry end of the lumber without being heated and without the addition of moisture. This subjects the lumber at the dry end to cold dry air, thus immediately lowering the humidity at this end to a dangerous point such as to incur liability of injury to the lumber. The addition of moisture by means of sprays to raise the humidity of the air at this end results, however, in raising the humidity at the green end of the kiln, thus practically terminating the drying entirely at the green end with the result that in such kilns practically all of the drying is caused to take place at the dry end, and the advantages of progressive drying are lost.

These various disadvantages in prior types and constructions of drying apparatus are avoided in accordance with the present invention by the development of a self-controlled recirculation of air actuated by differences in densities of the air. In the preferred form of drying apparatus, one or more by-passes are provided for by-passing hot humid air from the wet end of the apparatus to the dry end thereof. Withdrawal of the hot humid air is preferably accomplished by a throat injector connected to the wet end of the apparatus and through which the fresh air is caused to pass to withdraw the hot humid air and to deliver it to the dry end of the kiln. With this construction of apparatus in which recirculation is developed by the differences in densities of the partially counterbalancing columns of hot and cold air, the desired humidity conditions at the dry end as well as at the hot end are controlled in a self-regulating manner so that the liability of injuring the lumber through defective drying because of the operator's carelessness, inattention, or otherwise, is eliminated.

These various disadvantages in prior types and constructions of drying appara-

tus are avoided, in accordance with the present invention, by the development of a recirculating current of humid air from the wet end of the dryer through a by-pass to the dry end thereof. During the operation ⁷⁰ of the kiln upon a particular kind of lumber, the volume of humid air thus withdrawn through the by-pass may and preferably will be regulated so as to produce the requisite drying conditions in the kiln. By utilizing the differences in air pressure or vapor pressure as the effective means of causing movement of the hot humid air through the by-pass, the volume of humid air withdrawn is caused to vary with variations in the vapor pressures at the dry end of the kiln, so that in this manner deficiencies in humidity at the dry end are immediately and automatically compensated for in an exceedingly simple and yet highly efficient automatic manner, and one in which the liability of injuring the lumber through defective drying because of operating carelessness, inattention or otherwise, is eliminated. Furthermore, the entire kiln may be constructed at a minimum cost and operated at exceedingly low up-keep. The utilization of the heat content of the portion of the moist air by-passed from the wet end of the dryer is conducive to greater efficiency ⁸⁰ and to a minimum operating cost.

Referring to the drawings, the invention is, for the purpose of illustration, shown as embodied in a progressive kiln for lumber drying which comprises, in general, an elongated drying chamber 10, preferably of concrete or other insulating material having the usual openings 12, 14, at opposite ends thereof for the entrance and delivery of the lumber to be dried. Suitable doors or gates ¹⁰⁰ 16, 18, are provided for closing such openings.

The lumber is introduced in the usual manner through the opening 12, and is moved progressively toward the dry end of ¹¹⁰ the kiln upon suitable tracks 20, as shown in Fig. 1. Fresh air is delivered at the dry end of the chamber 10 through ducts 24 located at the bottom portion of the dryer and extended from the wet end thereof, as shown in Figs. 1, 4 and 5. The fresh air emerges from the top or upper surface of the ducts 24 through suitable slits or openings 26, where it rises through the lumber at the dry end of the dryer. Provision is made for spraying live steam into the drying chamber at both the dry and wet ends in order to provide the requisite heat and humidity for performing the drying operation. For this purpose spray nozzles 28 and 30, fed ¹²⁰ by steam lines 34, 36, are positioned at the desired points, as shown in Figs. 1, 4 and 5. The steam lines are provided with the usual control valves 38, so that both the heat and humidity within the kiln at the different ¹²⁵ 130

- points thereof may be controlled by the operator. The drying chamber may and preferably will be provided with the usual heating coils or piping 21 extending beneath the tracks 20 (see Fig. 1) and along the entire length of the chamber and by which the heat necessary for the maintenance of the desired temperatures and the final drying-out of the lumber may be obtained.
- 5 In order to provide positive internal circulation of air from the dry to the wet end of the kiln, and in order that deficiencies or variations in the air conditions at the dry end thereof may be automatically compensated for and the desired air conditions maintained, distributing ducts 40 are provided at the wet end of the kiln, at opposite side walls thereof, and extended downwardly and inwardly, terminating in the fresh air ducts 24 as shown. During the operation of the kiln upon any particular kind of lumber, the valves 38 controlling the steam sprays are adjusted to produce the desired humidity and temperature conditions within the kiln. Fresh air enters through the fresh air ducts 24 from the outside atmosphere with a strong rush because of the differences in vapor pressures due to the differences in temperatures at the opposite ends of the ducts 24, the temperature at the dry end usually approximating 200° F. As the fresh air rushes past the ends of the distributing ducts 40, the aspirating effect operates to withdraw some of the hot humid air from the wet end of the kiln, and to cause it to be delivered along with the fresh air through the slits or openings 26, and into the dry end of the kiln. The continued withdrawal of the air from the wet end during the operation of the kiln assists in producing a definite positive air movement from the dry to the wet end, a fact which is of immense importance for the most successful drying of the lumber. After the kiln is initially adjusted for operation upon a particular class of lumber, humid air of a definite volume and at a definite rate will be withdrawn from the wet end and delivered to the dry end. This initial adjustment together with the volume of fresh air introduced may be conveniently made by dampers 44, 46, hinged to partitions 48, 50, in the fresh air ducts 24, as shown. These dampers will preferably be arranged to be operated from without the kiln by suitable rods and connections not shown. When variations occur in the air conditions at the dry end of the kiln, corresponding variations in vapor pressures at the ends of the ducts 24 will occur, and because of the fact that the movement of the air through the ducts 24 and also the withdrawal of the humid air from the wet end of the kiln through the distributing ducts 40 are primarily actuated by differences in the densities of the columns of air at the wet
- and dry ends, it is apparent that when such variations occur they will be automatically compensated for, and the air conditions at both ends restored to normal in a positive, simple, self-regulating manner.
- 10 It will be observed that the cold inrushing fresh air as it is directed past the end of the distributing ducts 40 by the partitions 48, 50, performs an action similar to a throat injector. In order to increase the velocity of the air circulation through the portion of the ducts 24 beyond the distributing ducts 40, steam sprays 51 may and preferably will be provided therein, as illustrated in Fig. 4. If desired a throat injector of the form illustrated in detail in Fig. 6 may be employed, the cold air entering through the conduit 54 and the hot humid air being drawn through the surrounding conduit 56. In order to increase the velocity of the air, steam injectors or sprays 58 are preferably employed, arranged as shown in Fig. 6.
- 15 It will also be observed that the number and location of the conduits 40 through which the hot humid air is withdrawn may be varied to meet various conditions arising in practice, thus enabling air to be withdrawn from points of higher humidity and delivered to points of lower humidity.
- 20 During each cycle of the air circulation through the kiln, a portion of the humid air is drawn from the wet end upwardly through the exhaust flues 60 to the atmosphere. In this manner the excess moisture is continuously removed from the kiln.
- 25 While the invention has been illustrated and described as embodied in a progressive kiln for lumber drying, it will be understood that the invention may, with advantage, be embodied in apparatus for drying other material, within the scope of the following claims.
- 30 1. A drying apparatus comprising an elongated drying chamber for containing the material to be dried, means for admitting fresh air to the dry end of the apparatus, means for producing predetermined conditions of humidity and temperature within the apparatus, and means for developing self-controlled air recirculation actuated by differences in densities of partially counterbalancing columns of hot and cold air.
- 35 2. A drying apparatus comprising an elongated drying chamber for containing the material to be dried, means for admitting fresh air to the dry end of the apparatus, means for producing predetermined conditions of humidity and temperature within the apparatus, and means actuated by differences in density of partially counterbalancing columns of hot and cold air for withdrawing humid air from the wet end of the apparatus and delivering it with the fresh air to the dry end.

3. A drying apparatus comprising an elongated drying chamber for containing the material to be dried, means for admitting fresh air to the dry end of the apparatus, 5 means for producing predetermined conditions of humidity and temperature within the apparatus, and means actuated by differences in density of partially counter-balancing columns of hot and cold air for 10 adding humid air to the fresh incoming air delivered to the dry end.
4. A drying apparatus comprising an elongated drying chamber for containing the material to be dried, means for admitting 15 fresh air to the dry end of the apparatus, means for producing predetermined conditions of humidity and temperature within the apparatus, and means actuated by differences in density of partially counter- 20 balancing columns of hot and cold air for adding heat to the fresh incoming air delivered to the dry end.
5. A drying apparatus comprising an elongated chamber, a conduit for admitting 25 fresh air to the apparatus, and means for connecting the fresh air conduit and wet end of the apparatus for withdrawing humid hot air and delivering it to the dry end of the apparatus along with the fresh air.
- 30 6. A drying apparatus comprising an elongated chamber, a conduit for admitting fresh air to the apparatus, and means for connecting the fresh air conduit and wet end of the apparatus provided with a throat 35 injector for positive induction of air from the wet end actuated by means of the velocity of incoming fresh air.
7. A drying apparatus comprising an elongated chamber, a conduit for admitting 40 fresh air to the apparatus, and means for connecting the fresh air conduit and wet end of the apparatus for withdrawing humid hot air from a point of maximum air density in the wet end of the apparatus.
- 45 8. A drying apparatus comprising an elongated chamber, a conduit for admitting fresh air to the chamber, and means for connecting the fresh air conduit and wet end of the apparatus provided with a throat 50 injector for the positive induction of air from a point of maximum air density in the wet end of the apparatus.
- 55 9. A drying apparatus comprising an elongated chamber, a conduit for admitting fresh air to the apparatus, and means for connecting the fresh air conduit and wet end of the apparatus for withdrawing humid hot air from a point of high air density in the wet end of the apparatus.
- 60 10. A drying apparatus comprising a drying chamber, means for permitting movement of the material to be dried there- through, means for causing air movement through the material in a direction counter-current to the movement of said material, 65 and means for withdrawing air from the wet to the dry end of the apparatus operated and controlled by density differences of the air, said means including a by-pass conduit for by-passing air from a relatively humid 70 to a relatively dry portion of the chamber.
11. A drying apparatus comprising a chamber for containing material to be dried, and self-regulating means for controlling the humidity within the chamber by the distribution of moist air from a point of higher 75 to a point of lesser humidity.
12. A drying apparatus comprising a chamber, means for admitting fresh air to the chamber, and means for developing self-controlled air recirculation within the chamber comprising a throat injector cooperating with the chamber and the means for admitting the fresh air.
13. A drying apparatus comprising a 80 chamber for containing material to be dried, a conduit for delivering fresh air to one portion of the chamber, connections between a portion of the chamber, in which the humidity is relatively high, and a fresh air 85 conduit for withdrawing moist air and delivering it with the fresh air, and a steam spray in the conduit for increasing the velocity of air movement therein.
14. A drying apparatus comprising a 90 chamber for containing material to be dried, a conduit for delivering fresh air to one portion of the chamber, connections between a portion of the chamber in which the humidity is relatively high and the fresh air 95 conduit for withdrawing moist air and delivering it with the fresh air, and means in the conduit for increasing the velocity of air movement therein.
15. A drying apparatus comprising an 100 elongated chamber through which the material to be dried is progressively passed, means for admitting fresh air to the chamber, and means for developing self-controlled recirculation of the air longitudinally 105 through the elongated chamber.
16. A drying apparatus comprising an elongated chamber through which the material to be dried is progressively passed, 110 means for admitting fresh air to the chamber, and self-regulated means actuated by differences in the densities of partially counter-balancing currents of air for developing the circulation of the air longitudinally of the elongated chamber. 115
- In testimony whereof, I have signed my name to this specification.

JOHN B. WELCH.
